UNITED STATES PATENT OFFICE.

KARL BARKHAM, OF SOUTHAMPTON, ENGLAND.

GUARD OR BUFFER FOR TRUNK-PISTONS OR THE LIKE.

1,099,002.

Specification of Letters Patent.

Patented June 2, 1914.

Application filed February 14, 1914. Serial No. 818,770.

To all whom it may concern:

Be it known that I, KARL BARKHAM, engineer, a subject of the King of Great Britain, residing at 29 Bugle street, in the county 5 borough of Southampton, Hants, England, have invented certain new and useful Improvements in Guards or Buffers for Trunk-Pistons and the like, of which the following is a specification.

10 My invention relates to an improved guard or buffer for trunk pistons and the like.

The main object of my said invention is to provide a device for the protection of the outermost end of trunk pistons, plungers, and the like, when the said pistons or plungers are not in their proper working positions in the engines or machines which they may form part of. This device will protect the outermost end of the said pistons and the like from coming into violent contact with the connecting rod or its equivalent, through the said piston being able to swing beyond its proper working position, when as before described the piston is not 20 in its proper working position in the cylinder of the machine which it may form part of, or when the outermost end of the connecting-rod or its equivalent is disconnected from its proper working position, and so 25 allows the rod to come into contact with the piston as aforesaid.

I will describe my invention as applied to the trunk piston of an internal combustion engine.

30 In the accompanying drawings I have shown what I consider to be the best means of carrying out my invention, in which:—

Figure 1 is a cross sectional view of my improved guard or buffer. Fig. 2 an outside 40 elevation of same, viewed from bottom.

On the drawings Fig. 1 shows the guard as fixed to the lower or outermost end of a piston.

In carrying out my invention, I provide a 45 guard or buffer A, which may consist of one or more parts, which may be made of metal or other suitable material or materials. The guard or buffer A, will be placed inside the lower or outermost end of the piston B, and will be suitably fixed there for the time 50 it is required to remain in that position.

The guard or buffer will be of suitable size and made of suitable materials to suit the various requirements. I prefer the following 55 as the best way to accomplish the desired

result: I provide a metal ring A of an L shaped section. The foot of the L (C) will project outward. The vertical part of the ring A, which is at right angles to the foot C. of same, will normally be a little 60 greater in diameter than the inside of the piston B. A suitable small portion of the ring A. will be cut out or removed as in an ordinary piston ring (D on drawing). This will allow of the ring A, being compressed inward to a smaller diameter, and will also allow the ring A to envelop the connecting rod when required to do so.

The ordinary method of using the device will be as follows:—Taking it that the piston B. is about to be removed from its cylinder, upon the outermost end of the piston B. being withdrawn from the cylinder to a certain extent, the L shaped ring A. will be passed over the connecting-rod, and the 70 upper or vertical part of the said ring will be pushed into the outermost end of the piston B, the cut D in the ring A. as before described allowing it to be compressed to the required extent to allow of this being 75 done. The expansion will cause it to remain there. The lower part C. of the ring A. will be of greater diameter than the outside of the piston B. Thus it will not be possible to push the ring in beyond the required position, and also it will not be possible to replace the outermost end of the piston B. in the cylinder again until the ring or guard 80 A. is removed. Further:—the lower part C. of the ring or guard A. being of greater 85 diameter than the outside of the piston B. it will serve to protect the outside of same, and it will also protect the base of the piston B. from injury so long as it is in position. The ring A. being now in position as above 90 described will protect the piston B. from injury through the connecting rod coming into violent contact with same owing to the piston B. swinging on its gudgeon pin or hinge. The ring or guard A. can remain 100 in this position until the piston is replaced in the cylinder again. When this is done, as aforesaid, the lower end of the guard being of greater diameter than the piston, will not allow the said guard to be accidentally 105 left in the piston.

Although I have described this guard as being made in a certain manner, and of certain materials, the same may be made of any suitable material or materials, and the guard 110

or guards may be attached to the pistons by the use of spring clips, or in other suitable manner. The clips may form part of the guard A, or be separate as required. The L shaped ring or guard A, may be of a U shape if desired, and so inclose the outside as well as the inside of the piston.

I have also described my invention as applied to the piston of an internal combustion engine, but the same may be applied to the plungers of air compressors, pumps; and the like.

Having thus described my invention, what I claim as new therein, and desire to secure by Letters Patent is:—

1. A guard or buffer for use on trunk pistons comprising a ring adapted to be removably fitted upon the open end of the piston in concentric relation thereto.
2. A guard or buffer for use on trunk pistons comprising a ring adapted to be removably fitted upon the open end of the piston

in concentric relation thereto and having an angular cross section.

3. A guard or buffer for use on trunk pistons comprising a split resilient ring adapted to be removably fitted upon the open end of the piston in concentric relation thereto and having an L-shaped cross section.

4. A guard or buffer for use on trunk pistons comprising a split resilient ring adapted to be removably fitted upon the open end of the piston in concentric relation thereto and having an L-shaped cross section, the cylindrical portion of the ring fitting within the piston and the flat portion of the ring projecting across the end face of the piston.

In testimony whereof I have hereunto set my hand in presence of two subscribing witnesses.

KARL BARKHAM.
